[57] CLAIM

The ornamental design for a measuring tape guide and finger guide, as shown.

DESCRIPTION

FIG. 1 is a top, front, and left side perspective view of a measuring tape guide and finger guard showing my new design, the broken line showing of a tape measure is for illustrative purposes only and forms no part of the claimed design;

FIG. 2 is a left side elevational view;

FIG. 3 is a top plan view;

FIG. 4 is a right side elevational view;

FIG. 5 is a front elevational view;

FIG. 6 is a rear elevational view; and

FIG. 7 is a bottom plan view thereof.
